UNITED STATES PATENT OFFICE.

CHARLES W. MAYER, OF ROCHESTER, NEW YORK.

SATURATING-MACHINE.

1,288,642.

Specification of Letters Patent. Patented Dec. 24, 1918.

Application filed April 18, 1917. Serial No. 162,988.

To all whom it may concern:

Be it known that I, CHARLES W. MAYER, a citizen of the United States, residing at Rochester, in the county of Monroe and 5 State of New York, have invented certain new and useful Improvements in Saturating-Machines, of which the following is a specification.

This invention relates to saturating machines. Particularly it relates to machines for saturating paper or other fabricated web with substances which may be forced therewith by the combined action of heat and wiping-in mechanism. It is to be distinguished 10 from coating machines and from impregnating machines, as will be seen.

The object of my invention is to saturate the web with any desired substance capable of being forced into the same by using the 15 minimum amount of such substance, as distinguished from impregnating a web by submersion, or squeezing in, or any of the common methods which effect filling without regard to the quantity of material used. 20 Also, to be able to so saturate webs of the lightest tissue with the minimum amount of saturating material. As a concrete statement of this object, this machine fully saturates and renders waterproof a paper web 25 weighing but eleven pounds to the ream (24 x 36 inches) using less than one-half pound of wax to the ream. Or, further to show the attainment of this object, it saturates perfectly a web of paper tissue weighing 30 seven pounds to the ream (same size) without any strain upon the web or danger of tearing the same.

A further object of this invention is to effect such saturation without employment 35 of the various submersion, squeezing operations, coating and heating-in operations, and the like which produce either creasing, wrinkling, tearing the fabric, or distorting or buckling the same, especially with a very 40 light or tissue fabric; and furthermore, a most important object is to provide full control at all times with reference to speed, pressure and amount of saturating material employed.

50 A further object is to effect the saturation by the combined action of preheating and wiping-in the saturating material by a resilient buff while the web is firmly held against a heated drum.

55 I shall describe my invention adapted to saturating a web of paper with wax. But

while such is a main, typical use, I do not limit my invention thereto.

Since I employ a number of mechanisms well known in the art, I shall not describe 60 them in detail, but shall assume persons skilled in the art to be familiar therewith.

Referring to the drawing herewith, which is a side elevation, 1 is the stock spindle upon which the roll of fabric is placed. 65 This spindle is provided with adjusting and tensioning means for regulating the travel and tension of the paper. From this spindle the web passes over the preheating cylinder 2. This cylinder is heated by steam 70 or hot water in well-known manner. It is positively driven by gearing connecting it with the power-shaft 17 which is driven by a pulley 18 belted to any desired source of power.

75 After passing over this preheating cylinder and contacting a substantial arc of its surface, it passes down and around the large drum 3. This drum is likewise heated and heated to a high temperature, and is positively driven by gearing connecting it with the cylinder 2.

80 Thus before the web comes in contact with the buff 4, it is thoroughly heated through from both sides, so that it attains substantially the same temperature as the drum 3. This thorough preheating is essential to saturation with minimum amount of material because, whatever the temperature of the material applied, or whatever the temperature 85 of the buff, for unless the temperature of the web is substantially that of the melted material, full saturation will not occur and the capillary flow will be checked, or stopped, with the result that there will 90 be but semi-saturation or semi-coating. 9 is steam or water heated piping and the heat rising therefrom keeps the buff hot, and a deflector 10 directs the heat over the periphery of the buff.

100 The buff 4 is a built-up buff, made of factory cloth cut in disks, placed over a square shaft and compressed and held axially of the shaft. It is compressed sufficiently to give it rigidity, and still be sufficiently flexible to 105 flatten out in contact with the web to give a three or four inch rub against the web. Since this buff is run at the speed hereafter described, the centrifugal action tends to keep the saturating material from soaking 110 in toward the axis and thus keep it upon the periphery for application to the web.

It is essential that this buff be made of light, pliable material; otherwise it will rip the web when the web is a tissue or other fragile fabric.

5 A liquid-raising or coating-roll 5 rotates in a coating-pan which contains the coating and which is heated in well-known manner. This coating roll contacts the buff, and rotating in the same direction to that of the buff, applies the heated liquid to the buff.

10 An adjustable doctor 12 removes the surplus liquid carried up by the coating roll, and serves initially to regulate the amount of material to be applied.

15 The web, after passing over more than one-half of the periphery of the drum 3 after leaving the buff, during which time the saturating substance is thoroughly heated into the fiber, passes around the roll 14.

20 This roll 14 is gear-driven from the drum 3 and has the same peripheral speed. It is a cooling roll, cooled with water circulation; but under some conditions of fabric or saturating substance, it may be heated, through

25 hot and cold pipe connections in well-known manner, to prolong the heating-in process—permitting the roll next described to perform the cooling.

From the roll 14 the web passes around 30 the cooling roll 15. This roll is water cooled, is driven from the roll 14 by gearing, and has the same peripheral speed.

From the roll 15 the web passes to the wind-up roll 16, which is belt-driven by a 35 belt 19 driven from the shaft 17. An adjustable belt-tightener 20 is provided to regulate the pull of the wind-up roll 19.

The coating roll 5 is driven by sprocket and chain connection 21 with the shaft of 40 the drum 3, through changeable gearing of well-known type.

Adjustable scrapers 22 and 23 remove the saturating material that may adhere to the rolls 14 and 15, respectively.

45 With such general description, I will now describe the adjusting and change-speed mechanisms more specifically. The buff 4 is adjustable in two directions,—first, toward and away from the drum 3, and second, toward and away from the coating roll

50 5. Taking the latter adjustment first, the bearings of the buff 4 are mounted in yokes 6 which are pivoted on the shaft of the coating roll 5 and which have slots or openings 55 for the bearings of the buff 4. Rigidly connected to the bearings of the buff 4 are racks 7, which are in mesh with gears 24. Secured to the yokes 7 are gear-segments 26,

60 and in these gear-segments is journaled a transverse shaft 27, on which are rigidly secured the gears 24. A crank 28 on this shaft serves to rotate the gears 24 and thus to move the buff 4 radially toward and away from the coating roll 5. Gears 8 are rigidly 65 mounted on a transverse shaft 11 which is

journaled in bearings on the frame of the machine, and which shaft has a crank 13 which serves to rotate the gears 8, swinging the segments 26, and thus moving the buff 4 circumferentially of the coating roll 5 and 70 toward and away from the drum 3.

This adjustability of the buff serves not only to regulate the amount of material applied, but with the wear of the cloth of the buff in use, such adjustment is necessary, 75 as is also the other adjustment toward the drum 3.

While movement of the buff 4 toward and away from the coating roll 5 is tangential to the drum 3, the diameter of the drum is 80 so great and the adjustment of the buff so slight that no substantial disturbance of the adjustment between the buff and the drum occurs.

The change-speed gearing for varying the 85 speed of the buff is indicated in broken outline at 25, and the change-speed gearing for the coating roll is similarly shown at 29. In both cases the change-speed is well-known sliding-key construction which can be operated from one side of the machine while it is running. Other known forms of change-speed apparatus may be employed, but I have found this type the most adaptable.

While the operation will be clearly understood from the foregoing description, it should be noted that, aside from the buff and coating roll, all the other web-contacting rolls have a common peripheral speed, so that at whatever speed of operation, there is no undue strain upon even the lightest tissue. It is also to be noted that by having the buff and the coating roll both adjustable as to contact and as to speed as well, perfect saturation with minimum amount of material to 100 a degree wholly unattainable by the previous methods above referred to can be obtained.

Having thus described my invention, I claim:

1. In a web saturating machine, the combination of a heated drum over which the web travels, and a combined liquid-applying and buffing roll traveling in contact with the web on said drum. 110

2. In a web saturating machine, the combination of a pre-heating roll over which the web passes, a heated drum over which the web passes, said drum and roll being located on opposite sides of the web to heat both sides thereof, and a combined liquid-applying and buffing roll traveling in contact with the web on said drum. 115 120

3. In a web-saturating machine, the combination of a heated drum and a heated roll between which the web passes to heat both 125 sides thereof, and a combined liquid-applying and buffing roll coöoperating with the drum, the web passing between the drum and the buffing roll subsequent to its passage between the drum and the heating roll. 130

4. In a web-saturating machine, the combination with a relatively large heated drum, of a heating roll, and a combined liquid-applying and buffering roll, said rolls co-operating with the drum at different radial positions, the web passing first between the drum and heating roll and then between the drum and buffering roll.
5. In a web-saturating machine, the combination with a relatively large heated drum, of a heating roll, and a combined liquid-applying and buffering roll, said rolls co-operating with the drum at different radial positions, the web passing first between the drum and heating roll and then between the drum and buffering roll, the latter traveling at greater peripheral speed than the drum.
6. In a web-saturating machine, the combination with a drum over which the web travels, of a combined liquid-applying and buffering roll acting on the web as it travels on said drum, a liquid supply roll co-operating with the buffering roll, and means to adjust the buffering roll with respect to the drum and also with respect to the supply roll.
7. In a web-saturating machine, the combination with a drum over which the web travels, of a combined liquid-applying and buffering roll acting on the web as it travels on said drum, a liquid supply roll co-operating with the buffering roll, means to adjust the buffering roll radially with respect to the supply roll and tangentially with respect to the drum.
8. In a web-saturating machine, the combination with a drum over which the web travels, of a liquid-supply roller, and a combined liquid applying and buffering roll co-operating with both the drum and the supply roller, said buffering roll being adjustable with respect to either the drum or the roller, without materially varying its adjustment with respect to the other.

In testimony whereof I have hereunto set my hand and affixed my signature in the presence of two subscribing witnesses.

CHARLES W. MAYER.
